ISAAC ROBERTS.

ROTARY PUMP.

1,270,872.

Specification of Letters Patent.

Patented July 2, 1918.

Application filed June 24, 1915. Serial No. 36,062.

To all whom it may concern:

Be it known that we, ISAAC ROBERTS and WILLIAM SHAW, citizens of the United States, and residents of the city of New York, borough of Brooklyn, county of Kings, and State of New York, have invented certain new and useful Improvements in Rotary Pumps, of which the following is a specification.

10 This invention relates to what are generally known as rotary pumps, with more particular reference to pumps employed for the compression or exhaustion of air, although it will be apparent that a rotary 15 pump embodying our invention may be employed for many other purposes.

We have still more particularly in mind certain improvements in the general construction of the pump shown and described 20 in the patent to Crowell, No. 848,446, granted March 26, 1907, and the present invention has for its more especial objects, first, a constructional simplification of the Crowell device; second, the provision of means for regulating the amount of power utilized in 25 driving the device proportionately to the volume of fluid which is intended to be forced therethrough—and thus being able to economize in power when comparatively slight pressure or compression is desired; 30 third, to eliminate one of the usual bearings in the pump cylinder, and thereby minimize wear and the avenues of possible leakage, and, fourth, in general to provide a construction which while exceedingly simple 35 will prove durable and dependable in connection with the very largest as well as the very smallest sizes of pumps.

Our invention will be more readily understood by reference to the accompanying 40 drawings, forming a part of this specification, in which—

Figure 1 is a central sectional elevation of a rotary pump embodying our invention;

45 Fig. 2 is a transverse vertical section taken substantially on the line II—II of Fig. 1;

Fig. 3 is an elevation of the interior face of one of the removable cylinder heads or ends, hereinafter described;

50 Fig. 4 is an end elevation of Fig. 1, with the driving pulley removed;

Fig. 5 is a fragmentary view similar to Fig. 3, with the regulating valve in a different position of adjustment, and,

Fig. 6 is a detail view of the regulating 55 valve, as hereinafter described.

Referring now to the drawings in detail, numeral 11 designates a preferably integral cylinder, having one open end and for the purpose of this description shown as including a suitable base 12 which may be screwed or otherwise secured to any desired support. This member, which is preferably a finished casting, also includes a transversely disposed enlarged portion on its upper side to provide chambers 13 and 14, which are open to the cylindrical pump chamber 15, these chambers also having ports 16 and 17, respectively, one thereof leading through any suitable connecting means to a source of air 70 or other fluid supply and the other leading through suitable connecting means to the compression chamber or to such other ultimate destination as is intended for the fluid. Of course, if the device is to be operated as 75 a vacuum pump, one of these ports will lead to the chamber from which it is desired to exhaust the air, and the other will lead to atmosphere.

The cylinder head or end 18, which closes 80 and seals the open end of the pump cylinder, is designed to be secured in place by means of screws 19, and preferably forms an integral part of the member which includes the shaft bearings 20 and 21. This 85 member also includes a U-shaped portion 22 to permit of the mounting of a driving pulley 23 between the shaft bearings aforesaid. It will be noted that this entire member is supported by the cylinder 11. 90

The driving shaft 24 is mounted eccentrically with respect to the cylindrical pump chamber, and carries at its end, within said chamber, the substantially solid drum or cylinder 25. This drum 25 is of substantially 95 the same width as that of the pump chamber 15, fitting within said chamber as snugly as is practicable, considering that the drum must rotate very rapidly within said chamber and the friction must not be excessively great. The diameter of the drum 25 is somewhat less than the diameter of the chamber 15, and the former is so located in the latter that the top faces thereof are substantially in contact, and what may be termed a crescent-shaped space is provided between the drum and the circular wall of the chamber, substantially as shown in Fig. 2. 100 105

The drum 25 is provided with a plurality—preferably three—of radially disposed longitudinal slots, located equidistantly from each other. Loosely fitting within each of the three slots is a free piston 26, of approximately the same dimensions as the slot, having a limited, sliding radial movement therein and rotating with the drum or cylinder 25. At the bottom of each slot is provided a small pocket or recess for the reception of a compression spring 27, the yielding forces of which constantly tend to impel the piston in a direction away from the center of the drum 25. It will be apparent, therefore, that as this drum is rotated within the chamber 15, each piston will be yieldingly held against the peripheral wall of said chamber, moving in and out of its retaining slot as it approaches or recedes from the position where said drum is in contact with said wall.

We are aware that no broadly new principles are involved in the construction of rotary pump described above. However, it has been found, particularly in connection with pumps of larger sizes, that it is sometimes necessary to reduce either the volume of the fluid being forced through the pump or the pressure to which the same is subjected on the discharge side of the pump. Obviously, this may be accomplished by reducing the velocity at which the pump is driven, but with rotary pumps of this type a reduction of speed has been found to be undesirable and not economical. Furthermore, any ordinary choking of the supply for the purpose set forth still renders necessary the utilization of substantially the same amount of driving power, and one of the features of the present invention grows out of our effort to conserve power when the capacity of the pump has been reduced.

For this purpose, we provide a bore 28 in the cylinder head or end 18, and cut grooves or channels 29 and 30 in the interior face of said head, leading from the spaces on opposite sides of the drum 25 to the bore 28. Within this bore we mount the rotary valve 31, the inner end of which abuts against the face of the drum 25 and which may be rotated to open and close the ends of the channels 29 and 30 at the bore 28. This valve is preferably provided with a head 32, on the exterior face of the cylinder head or end 18, whereby said valve may be operated by means of the small lever 33.

It will be apparent that when the valve is in the position indicated in Fig. 5, the end of the groove 29 is closed, and there is no direct means of communication between the spaces on opposite sides of the drum—these spaces being at all times separated by one of the pistons 26. Under these conditions,

the device is designed to be worked to its full capacity.

When it is desired to reduce this capacity, the valve 31 is rotated to open the closed end of the groove 29, and thus provide an open passage between the spaces referred to on opposite sides of the drum. The extent to which the valve is opened may obviously be regulated from an exceedingly small opening to that of substantially full extent, as illustrated in Fig. 3.

As is doubtless apparent from the drawings, if not otherwise well known, if the drum 25 is rotated in the direction of the arrow, the chamber or space above the piston which has just cleared the chamber 13, will be constantly increasing in size. Therefore, air or other fluid will be drawn in through the port 16 until this space reaches its maximum size, which happens just after the next succeeding piston has cleared the opening from the chamber 13. From this point on, there is little change in the size of the containing chamber until the foremost piston reaches the opening to the discharge chamber 14, whereupon the space within the cylinder is decreased in size to drive the air or other fluid from the port 17.

It will be seen that if the valve 31 is rotated to open the end of the groove or channel 29, at least a part of the fluid in the discharge space will be directed back into the intake space, the volume of this shunted fluid being capable of regulation by means of the valve 31. Therefore, the amount of power required to drive the chamber may be materially reduced by using a portion of the compressed fluid to assist in the driving-operation—and this without reducing the velocity of the moving parts. In the larger sizes of blowers and compressors this is a matter of no inconsiderable importance.

In addition to the general simplicity of construction of the device shown and described, attention is again called to the fact that the driving shaft is mounted in bearings which are carried by one only of the cylinder heads, the other head being therefore imperforate, and as these bearings are the parts subject to the greatest wear, it will be apparent that I have reduced by one-half the sources of ultimate excessive leakage and therefore the number of parts necessary to be replaced on this account.

Many modifications of minor details of our improved rotary pumps will doubtless readily suggest themselves to those skilled in the art to which it appertains, and we therefore do not desire to limit our invention to the specific construction herein shown and described.

We claim as new and desire to secure by Letters Patent:

1. In a rotary pump, in combination,

piston carrying drum, a cylinder providing a pump chamber in which said drum is eccentrically mounted, cylinder heads one of which is provided with intersecting grooves 5 leading from opposite sides of the pump chamber, and a valve at the intersection of said grooves adapted to regulate the volume of fluid that can pass through said grooves from one side of the pump chamber to the other.

2. In a rotary pump, in combination, a piston carrying drum, a cylinder providing a pump chamber in which said drum is eccentrically mounted, cylinder heads one of 15 which is an integral part of said cylinder, the other being detachable and provided with intersecting grooves leading from opposite sides of the pump chamber, and a valve at the intersection of said grooves 20 adapted to regulate the volume of fluid that can pass through said grooves from one side of the pump chamber to the other.

3. In a rotary pump, in combination, a piston carrying drum, a cylinder providing 25 a pump chamber open at one end in which the drum is eccentrically mounted, a detachable head adapted to close the open end of the cylinder and provided with intersecting grooves leading from opposite sides of

the pump chamber, and a valve at the intersection of said grooves adapted to regulate the volume of fluid that can pass through said grooves from one side of the pump chamber to the other.

4. In a rotary pump, in combination, a piston carrying drum, a cylinder providing a pump chamber open at one end in which the drum is eccentrically mounted, a detachable head adapted to close the open end of the cylinder, means carried by said head for 35 rotatively supporting the driving shaft for said drum, the inner face of said head being provided with intersecting grooves leading from opposite sides of the pump chamber, and a valve at the intersection of said 40 grooves adapted to regulate the volume of fluid that can pass through said grooves from one side of the pump chamber to the other.

In testimony of the foregoing, we have 50 hereto set our hands in the presence of two witnesses.

ISAAC ROBERTS.
WILLIAM SHAW.
